(57) **CLAIM**

The ornamental design for a bottle, as shown and described.

DESCRIPTION

FIG. 1 is a front elevational view of a bottle showing my new design therefor;

FIG. 2 is a left side elevational view thereof;

FIG. 3 is a right side elevational view thereof;

FIG. 4 is a bottom plan view thereof;

FIG. 5 is a top plan view thereof;

FIG. 6 is a view similar to FIG. 1 of a second embodiment of my design;

FIG. 7 is a left elevational view thereof;

FIG. 8 is a right elevational view thereof;

FIG. 9 is a bottom plan view thereof; and,

FIG. 10 is a top plan view thereof.

1 Claim, 8 Drawing Sheets
